OTTO MANTIUS, OF NEW YORK, N. Y.

METHOD OF MAKING FIBER BOARD.

Application filed March 16, 1928. Serial No. 262,223.

This invention is a method for making fiber board and is directed more particularly to the removing of excess moisture and forming of the board in sheets after the pulp has been 5 previously prepared in any suitable conventional apparatus.

In the manufacture of fiber board, the pulp having been produced in any one of several ways is hydraulically pressed or passed between a succession of rollers, the purpose of which is to squeeze out the excess water and form the pulp into a sheet. Pulp, as operated upon in this manner, contains about ninety 15 per cent of water and it is to remove this water and form the pulp into sheets that it is acted upon by rolls or otherwise as stated. The common practice is to pass the pulp between a succession of coacting rolls, that is to say, the pulp after passing between one pair 20 of coacting rolls travels for a distance without pressure and thereupon passes between a second set of coacting rolls. This operation is repeated, so that the pulp is successively passed between coacting pairs of rollers positioned at appreciable distances apart. The 25 purpose of rolling the pulp as stated is to free the pulp from its water content.

During the operation of the pulp by a machine such as stated, the passing of the pulp 30 between any particular set of rolls serves to squeeze out an appreciable portion of the water by highly compressing the pulp. I have noted, however, that as soon as the pulp passes from any particular set of rolls, its 35 spongy nature causes it to immediately expand in thickness so that it acts after the manner of a sponge to again suck up a considerable amount of water before it is acted upon by the next set of rolls which are meanwhile 40 squeezing out water from a forward portion of the pulp and feeding it to a following portion which is meanwhile expanding and sucking up the water. This operation occurs between each pair of rolls and materially lowers 45 the efficiency of the machine for the reason that the pulp is not subjected to successive drying, but as a matter of fact is dried to a certain extent, thereupon wet again, then dried to a further extent, then wet again, etc., 50 as it passes through successive rolling operations as stated. As a result, the prior machines of the character which I have referred to, and which constitute the standard apparatus of the prior art, are made quite heavy

and embody a relatively large number of rolls, 55 in order to obtain a product which will be commercially satisfactory.

My discoveries along the lines stated have convinced me that the only satisfactory method of forming sheet fiber board from 60 pulp in a continuous manner is to effect the drying of the pulp in a continuous manner. That is to say, to so act upon the pulp that it is subjected to a continuously increasing pressure without cessation in the application of 65 pressure.

This constitutes the broad concept of the present invention embodying a method of forming a relatively dry web from paper pulp 70 which consists in moving the pulp continuously along a predetermined path and subjecting it during such passage to constantly increasing pressure which has the effect of progressively removing the water from the pulp and simultaneously forming such pulp 75 into a continuous web or sheet suitable for the final drying operation.

In practically carrying out the present invention, I find it desirable to manipulate the pulp in such manner during the application 80 of pressure thereto as stated, so that the pulp is acted upon with increased pressures for a predetermined portion of its travel in order to reduce the pulp ribbon to the desired thickness and after this has been accomplished, the 85 web thus formed is maintained for a further period of its travel at such predetermined thickness in order that the web may be "set" at such thickness, so that when it is delivered from the last mentioned operation, it will not have an appreciable tendency to expand, but will retain substantially the thickness which 90 has been "fixed" in the manner specified.

As a further step in the method of this invention, I remove the water which is squeezed 95 out from the pulp in such manner that it will not have a detrimental further wetting effect upon the pulp that is being fed to the drying and forming operations stated.

Features of the invention, other than those 100 adverted to, will be apparent from the hereinafter detailed description and claims, when read in conjunction with the accompanying drawings.

The invention may be practically carried 105 out with various forms of apparatus, but an apparatus which has been found highly satisfactory is shown in the accompanying draw-

ings. This apparatus is to be understood, however, as illustrative, only, and not as defining the limits of the invention.

Figure 1 is a diagrammatic view of apparatus for carrying out the present invention, portions of the frame of the apparatus being shown in phantom, while other portions are shown in central section. All details have been omitted in this showing in the interests of clearness.

Figure 2 is an enlarged vertical section showing the pressure applying rollers and the means whereby they are supported in coacting relation.

Figure 3 is a plan view of the lower set of rolls shown in Figure 2.

The machine shown in the drawings embodies a suitable frame. The frame is illustrated as embodying castings 1 and 2 connected together by side plates 3, one of which is positioned at each side of the machine and is rigidly bolted to the castings 1 and 2. The castings 1 and 2 are also duplicated at opposite sides of the machine, so that these parts when firmly bolted together constitute collectively the rigid frame of the apparatus.

Extending transversely of the machine and rigidly bolted at its opposite ends to the side plates 3 is a bed 4 preferably in the form of a casting suitably ribbed to impart strength thereto, but cored out so that it will not be excessively heavy.

Positioned in spaced relation above the bed 4 is what may be termed a cross head 5. This cross head extends transversely of the machine and is of the same general form as the bed 4 although inverted with respect thereto. This cross head normally seats on the upper edges of the side plates 3 and is held to this seat by a number of springs 6 which embrace threaded posts 7 as shown. These posts are anchored at their lower ends in the side plates 3 and project upwardly in parallel vertical relation to one another. One spring 6 is coiled about each post and a nut 8 cooperates with the upper threaded end of each post in order that the springs may be placed under the desired tension sufficient to hold the cross head seated upon the upper edges of the side plates 3 while permitting of an upward yielding movement of the cross head in the event that the rollers which are associated therewith, as hereinafter more fully described, engage some non-yielding foreign substance which may be found in the pulp on which they are adapted to operate. The normal position of the cross head is that wherein it rests upon the upper edges of the side plates 3 and this position may be regulated by introducing shims between the upper edges of the side plate and the cross head for reasons hereinafter more fully explained.

Mounted on the under face of the cross head 5 and on the upper face of the bed 4 are a plurality of rollers which may be secured to these

parts in any suitable manner, but may conveniently be mounted as shown in Figs. 2 and 3. In these figures, 9 and 10 designate castings suitably reinforced and provided with holes 11 through which screws or bolts may be passed to secure the castings to the bed and cross head.

Each casting is formed to provide bearings for a number of rollers mounted in the casting in staggered relation to one another as shown in Fig. 3. That is to say, the rollers 12 are positioned in staggered relation to the rollers 14, i. e., the axes of the rollers 12 lie midway between the axes of the rollers 14, as viewed in Figs. 3 and 2. The rollers 12^a and 14^a are similarly disposed in the holder 9. The rollers 12' and 14' are the same as the rollers 12 and 14 in structure and are disposed in substantially the same manner except that their axes are mounted in slightly different relation presently to be explained and the same holds true of the relationship between the rollers 12^a and 14^a as compared with the rollers 12^a and 14^a.

In a machine such as shown in Fig. 1, several holders of the character described are employed. That is to say, for example, six of such holders are mounted side by side on the bed 4 as shown in Fig. 3 and are firmly secured to the bed in such manner that the axes of the respective rollers will extend in a direction transversely of the machine. A like number of holders 10 are secured to the under face of the cross head 5, so that the upper face of the cross head will also carry a large number of rollers positioned in staggered relation on these respective parts, but with the corresponding rollers of both parts in juxtaposed relation to one another. Thus each roller 14 will be directly below its corresponding roller 14^a and each roller 12 will be similarly disposed with respect to its corresponding roller 12'. It will be noted that the rollers 12 and 14 and 12^a and 14^a are so mounted on their respective holders that they are of progressively decreasing distance apart in a direction from left to right in Figures 1 and 2. This will be apparent from the latter figure, wherein 15 designates a plane in which the axes of the rollers 12^a and 14^a are included while 16 designates the plane in which the axes of the rollers 12 and 14 are included.

It will be noted that these planes converge to the right in this figure. Attention, however, is called to the fact that the axes of the rollers 12' and 14' are not included in the plane 16, but in another plane 17, while the axes of the rollers 12^a and 14^a are not included in the plane 15, but in a different plane 18. These planes 17 and 18 are preferably parallel with respect to one another. As a result, the rollers 12, 14 and 12^a and 14^a present a tapering mouth to material fed thereto in the direction of the arrow 19 in Figure 2 and that these rollers are progressively

closer to one another as far as the line 20. Beyond this line are located the rollers 12', 14' and 12², 14² which are spaced equal distances apart in a vertical direction.

5 The upper and lower roll sets which I have described as mounted on the bed and cross head of the machine are spaced apart predetermined distances and between them pulp is adapted to be carried on endless conveyor belts which travel between the rolls. These belts which are designated 21 and 22 are preferably slat conveyors. They may be conveniently formed of steel slats positioned edge to edge and extending transversely of the machine and mounted in this relation upon endless conveyor chains which serve to hold them in the desired relation and impart movement thereto.

10 The chains of the upper conveyor 21 are passed about sprockets 23 carried by the frame of the machine, while the chains of the lower conveyor are passed about sprockets 24 similarly mounted, as best shown in Fig. 1. These sprockets are driven through belts 25 or chains 25 from any suitable source of power connected to shafts 26 and 27, so that the upper and lower conveyors are caused to continuously travel as shown.

15 Because of the pronounced liquid condition of the pulp to be operated upon, I find it desirable to associate with the conveyors feed aprons. These feed aprons are in effect endless conveyors. They are designated in the drawings by the reference characters 28 and 29 and are preferably wire mesh aprons. As shown in Figure 1, they are led about appropriate directional and tensioning rolls and pass between the operative reaches of the upper and lower conveyors 21 and 22. The purpose of these mesh aprons is to carry the pulp into cooperative relation with the conveyors 21 and 22 in order that the pulp may be fed to the pressure zone and to thereafter remove the finished sheet from the zone of pressure and feed it to an appropriate discharge table or out of the machine.

20 In practically operating the apparatus which I have described, the fiber pulp after having been suitably collected on a vacuum suction feeder, or otherwise, and thereby formed into a ribbon of from one to two inches thick is fed down a table 30 or in any other suitable manner to the lower apron 29 and is immediately carried by this apron into cooperative relation with the upper apron 28. Thereafter these two aprons conjointly serve to move the pulp ribbon in the direction of the pressure rolls and thus carry it between the lower reach of the upper conveyor 21 and the upper reach of the lower conveyor 22. This ribbon of pulp generally contains about ninety per cent of water and the aprons 28 and 29 are thus well suited to handle the pulp in this wet, semisolid condition.

25 As the pulp is carried by the upper and

lower slat conveyors in a direction to the right in Fig. 1, it is gradually compressed and the water therein is gradually squeezed out so that by the time the pulp reaches the first of the pressure rolls, it has been freed of 70 some of its water content and in this condition it passes into the tapering mouth between the pressure roll sets. The slats of the conveyors are substantially rigid and are sufficiently wide to bridge over adjacent rolls 75 of these sets. As a result the continued passage of the pulp into the constricted zone of pressure brings about the application of a constantly increasing amount of pressure which is not relieved, but in fact constantly 80 increases from the time the pulp enters the pressure zone between the rollers until the time that it reaches the point designated by the line 20 in Figure 2.

85 By this time, the pulp has been subjected to a steady increase in pressure. As it continues beyond the line 20 in Fig. 2, the pressure is maintained substantially constant until it passes beyond the last rollers 14' and 14². As the pressure constantly increases 90 as the pulp moves along, the water is squeezed out of the pulp in substantially a constant stream and the pulp becomes dryer and dryer as it approaches the end of the pressure zone. The water thus squeezed from the pulp is 95 drained through the small cracks between the slats of the conveyors. From the lower conveyor it will drop by gravity while from the upper conveyor, the water is removed by a suitable suction pump acting through a suction pipe 31. It will be noted from the drawings that the web travels in an upwardly inclined direction so that the water squeezed out between the slats of the upper conveyor 100 will flow down to the pipe 31.

105 I wish to particularly stress the fact that when the parts are associated as described, the pressure rolls so act upon the slats of the conveyor that once they have entered between the upper and lower pressure rolls, the pressure is never relieved from these slats until the time they leave the pressure zone and pass from between said rollers.

110 On the contrary, the pressure is constantly increased without diminution at any point 115 until the line 20 is reached, beyond which the pressure is maintained constant until the slats leave the last rolls in the pressure zone. Thus the structure shown not only serves to exert constantly increasing pressure for the purpose of drying the pulp by squeezing the water therefrom, but it simultaneously serves the purpose of forming the pulp into a solid sheet and gradually decreasing such sheet to the predetermined thickness, this thickness 120 being maintained during the latter part of the pressure zone in order to produce a fixed "set" in the finished product.

125 After leaving the pressure zone, the moist sheet or web is led by the lower apron out of 130

the machine to be received at a suitable discharge table or otherwise. It is thereupon cut to suitable sizes and put in a drying oven as in prior practice.

5 From the foregoing detailed description of the present invention, it will be apparent that the disadvantages of prior practice to which I have referred are wholly eliminated by the method of this invention. The formation of 10 the sheet is efficiently accomplished and a uniform product is produced through the employment of relatively simple mechanism. I have not considered it necessary to show all of this mechanism in detail as this invention is 15 drawn to the method while the apparatus forms the subject matter of a companion application Serial No. 262,924, filed March 16, 1928. It may be stated in passing, however, that while the taper of the pressure mouth is 20 substantially fixed in the apparatus as shown, the thickness of the finished sheet may be controlled by introducing shims between the cross head and the upper edges of the side plates 3.

25 The purpose of the springs 8 is to permit the cross head to yield in the event that hard extraneous substances are entrained and carried along by the pulp into the pressure zone. If an unyielding arrangement were em- 30 ployed, breakage of the apparatus might result, but with the arrangement as shown, the parts will yield and permit the passage of the extraneous matter without damage to the apparatus.

35 The apparatus which I have illustrated for carrying out this method embodies mechanism for causing pulp to travel between and with substantially plane hard surfaces positioned in converging relation to one another 40 and adapted to simultaneously travel in a direction of their convergence, so that by this apparatus I am able to mechanically carry out the method hereinbefore defined by the slat conveyors as shown. This apparatus is 45 highly efficient in carrying out the method of this invention, but I wish it understood that the method is not limited to this particular apparatus, but is rather to be construed as fully commensurate with the appended 50 claims.

Having thus fully described the invention, what I claim as new and desire to secure by Letters Patent is:

1. The herein described method of making

fibre board which consists in feeding pulp in 55 a loose wet condition along a predetermined path, subjecting said pulp during a portion of such movement to constantly uniformly in- 60 creasing pressure for the purpose of squeezing excess water from the pulp and to form the 65 pulp into a sheet, and applying to said pulp during a further portion of its movement along such path a substantially constant pres- 70 sure in order to "set" said sheet at the desired thickness.

2. The herein described method which con- 75 sists in feeding pulp along a predetermined path, subjecting said pulp during its move- 80 ment along a portion of its complete travel to constantly uniformly increasing pressure to squeeze out excess water from the pulp and form the pulp into a sheet, and applying to the pulp for a further portion of its travel a constant pressure substantially equal to the 85 maximum pressure produced in forming the 75 sheet in order to "set" the thickness of such sheet.

3. The herein described method which con- 90 sists in causing pulp in a loose, wet condition to travel along a predetermined path, subject- 95 ing pulp during the portion of such travel to constantly uniformly increasing pressure, starting at a substantially zero pressure and finishing with a predetermined maximum pressure, and maintaining such maximum 85 pressure for an appreciable distance in the travel of the material whereby the loose pulp is partially dried and formed into a sheet and the thickness of the sheet thereupon set.

4. The herein described method which con- 90 sists in causing substantially plane hard sur- 95 faces positioned in converging relation to one another to simultaneously travel in the direc- 100 tion of their convergence, and introducing pulp between the said surfaces whereby the movement of said surfaces will cause the pulp to be subjected to constantly uniformly in- 105 creasing pressure which will free the pulp of excess water and form the pulp into a solid sheet, and thereafter causing the sheet thus formed to travel for a distance between hard, unyielding surfaces spaced a uniform dis- 110 tance apart in order to "set" the sheet thus formed.

In testimony whereof I have signed the 105 foregoing specification.

OTTO MANTIUS.
